Albert S. N. Olson,
by Chas. Williamson, Atty.

UNITED STATES PATENT OFFICE.

ALBERT S. N. OLSON, OF CHICAGO, ILLINOIS.

LITHOGRAPHIC-PRINTING PRESS.

Application filed March 28, 1919. Serial No. 285,830.

To all whom it may concern:

Be it known that I, ALBERT S. N. OLSON, of Chicago, in the county of Cook and in the State of Illinois, have invented a certain new and useful Improvement in Lithographic-Printing Presses, and do hereby declare that the following is a full, clear, and exact description thereof.

My invention relates to lithographic or planographic printing, that is to say to printing from the etched or engraved surfaces of thin metal sheets, such as zinc or aluminum. With such methods or appliances as ordinarily used, it is commercially impracticable to do small jobs in small quantities, because they are not profitable. By my invention, however, it is rendered possible to do jobs of small dimensions, and when small quantities are desired, with profit and by the use of the ordinary platen letterpress. Generally stated, the object of my invention is to enable lithographic or planographic printing to be done economically so as to render it available in fields from which it has heretofore been excluded, because of cost, and, in particular my object is to enable such printing to be done with an ordinary platen letterpress. A special object of my invention is to enable offset lithographic printing to be done on an ordinary platen letter press.

In the accompanying drawings I illustrate one way by which my invention can be carried out in connection with and in the form of an attachment to an ordinary platen letterpress in which drawings:—

Fig. 1 is a perspective view of an ordinary Gordon letterpress provided with an attachment embodying my invention;

Fig. 2 is a front view of the chase and bed for holding the engraved metal sheet;

Figs. 3 and 4 are respectively side elevations thereof, showing the lowered and raised positions respectively of bearers for preventing contact of the ink rollers with the printing form when that is desired;

Fig. 5 is a detail view in vertical section on the lines 5—5 of Fig. 2;

Fig. 6 is a vertical section on the line 6—6 of Fig. 2;

Fig. 7 is a detail view in side elevation of the mechanism for raising the movable bearers from the feed board of the printing press; the position of the parts when the bearers are raised being shown;

Fig. 8 is a similar view showing the position of the parts with the bearers lowered;

Fig. 9 is a detail top plan view of the inking and dampening rollers;

Fig. 10 is a detail view thereof in side elevation;

Fig. 11 is a detail view of one of the bearer-bars for controlling the positions of the inking and dampening rollers in passing over the inking plate or disk;

Fig. 12 is a detail view in side elevation of one of the bracket devices for supporting and attaching the dampening rollers to the inking rollers;

Fig. 13 is a front elevation of the water fountain for supplying water to the dampening roller;

Fig. 14 is a vertical section through the fountain with parts in side elevation;

Fig. 14^a is a detail view in vertical section of the lower part of said fountain;

Fig. 15 is a detail view in section of one of two similar devices at each side of the press frame for attaching the water fountain thereto;

Fig. 16 is a detail top plan view thereof;

Fig. 17 is a detail view in side elevation of the dampening roller bearer-bar;

Fig. 18 is a side elevation of the blanket carrying frame and its supporting and actuating devices, and the gripper for holding the paper to the platen;

Fig. 19 is a detail view of one of the frame latch wheels;

Fig. 20 is a detail side view of one of the paper grippers;

Fig. 21 is a like view of the spring that acts on the grippers;

Fig. 22 is a detail view of part of the blanket carrying frame, and its rotating devices;

Figs. 23—24, are detail front and edge views respectively, of the wheel and gear for rotating the blanket carrying frame;

Fig. 25 is a detail view, in perspective of 100

the mechanism for raising, lowering, rotating and locking the blanket frame;

Fig. 26 is a detail view of the blanket rotating bars of said mechanism;

Fig. 27 is a front elevation of a portion of the blanket frame and its said operating and locking mechanism;

Fig. 28 is a detail view, in perspective of one corner of the blanket frame, with the parts shown separated;

Fig. 29 is a like view of one of the side supporting bars;

Fig. 30 is a side elevation of one of the devices to rotate the wheel-latch;

Fig. 31 is a detail perspective view of the actuating device attached to the press pitman for actuating the blanket frame mechanism.

The Gordon press shown in the drawing being a well-known construction needs no particular description beyond saying that it comprises a frame 10, a chase 11, an ink-disk 12, the swinging platen 13 and power-operated platen swinging mechanism which need not be particularly described. The discovery which I have made which results in the attainment of the object of my invention, is that by supporting a thin metal sheet having an inked printing face upon a plane or flat surface and pressing thereagainst the sheet to be printed by a flat or plane platen, and with the even pressure lithographic or planographic printing can be successfully and satisfactorily done. The important considerations in the press, therefore, are its possessions of the characteristics of two opposing flat or plane surfaces between which the engraved plate and the sheet to be printed are pressed. Since lithographic or planographic printing requires the application of water to the printing plate or form, it will be found that my invention provides moistening means, and it will also be found that a special construction of chase is desirable but no substantial alteration or modification of the press as constructed for ordinary use is required, so that for the practice of my invention the appliances or devices necessary may exist in the form of an attachment to the press.

Referring particularly to Figs. 1 to 4, it will be seen that the chase 11 has the usual flat rectangular frame form. Within it is secured a bed 14 in the form of a solid slab or block, whose outer face is flat or plane, and is situated substantially type-high. Stretched tightly over the flat outer face of the bed 14 is the sheet metal printing plate 15, its top and bottom edges being clamped securely so that it is stretched tight and smooth over the bed. The bottom edge of said plate is clamped between the bottom of the bed 14 and a clamping bar 16. The lower side of the clamping bar 16 has several inclined or wedge-shaped surfaces and between

the same and the adjacent bottom bar of the chase is a longitudinally slideable bar or quoin 17 with similarly inclined faces that engage those of the clamping bar 16. The clamping bar 16 is restrained from endwise or sidewise movement by several pins 18 which are secured to the bottom of the chase and pass through slots 19 in the quoin 17 and into holes in the bar 16. In a space between the top of the bed 14 and the top bar 75 of the chase there is a vertically movable clamp that consists of two bars 20 and 21 with correspondingly shaped irregular opposing faces between which the upper edge of the printing sheet 15 is gripped and securely held by the action of several screws 22, that join the two bars. At intervals the upper bar of the chase has several vertical screws 23 whose lower ends engage threaded holes in the clamp bar 20 so that by turning 85 said screws 23 in the proper direction to do so the clamping bars gripping the upper edge of the printing plate will be drawn upward, and thus stretched tightly over the flat face of the bed 14.

There are two leather-covered ink rollers 24 journaled as usual at their opposite ends in blocks 25, that are carried by the usual lever at each side of the press, upon the spindles or stocks of which are mounted bearing 95 rollers 26, that pass over the usual beaters 27 on opposite sides of the press, said inking rollers 24 as usual passing back and forth over the ink disk and the printing form. In advance of the inking rollers 24 is a felt covered moistening roller 28 which at each end has a stock or spindle that is journaled in a block 29, that is connected with and receives motion from the roller vibrating lever. The dampening roller stock or spindle is seated 100 in an open ended slot 30 in the block 29, the open end being closed by a removable plate 31, this arrangement being employed for the application and removal of the block 29 without removing or disturbing the dampening roller. Each block 29 has on its outer side an arm or extension 32 which has journal holes near its ends for the pintles of two small rollers that lie parallel, and have contact, with the dampening roller. One of the 115 small rollers 33 aids in distributing moisture over the surface of the dampening roller (moisture being supplied thereto as herein-after described) said roller 33 being preferably felt covered, while the other roller 34 is of metal and performs the function of cleaning ink from the surface of the dampening roller. Each arm 29 at one end is forked by the provision of a slot 35, so that it may straddle the pintle of the adjacent inking roller (see 125 Figs. 10 and 12).

The small rollers 33 and 34 are preferably pressed yieldingly against the dampening roller 28. In the device shown in the drawings, this is accomplished by mounting the 130

arm 32 on a threaded stud 36 fixed at one end to the block 29, and interposing a spring 37 on the stud between a nut 38 on the stud and the lower one of two ears 39 on the arm, 5 through which the stud passes.

When the dampening roller traverses the ink-disk, it should not touch the inked surface thereof. To secure this result, an arm 40 may be secured to the press at each side, 10 which extends upward and rearward, parallel with the inked face of the disk, forming in effect, an extension of each bearer 27, with the top edge of which a roller 41 on the pintle of the dampening roller will 15 engage, as the adjacent smaller roller 42 which cooperates with the bearer 27, leaves the latter, and thereby the dampening roller lifted enough above the ink-disk to clear the same.

20 The dampening roller is supplied with water from a fountain situated below the chase 11, to and from which said roller is moved. Said fountain (see Figs. 13 and 14) comprises an oblong box or tank 43 which 25 on its front side has an exposed portion of an endless band 44 of felt, or other water absorbent material, into contact with which the roller 28 is brought. The band 44 passes about a roller 45 in the bottom, water 30 holding portion of the tank, and about a roller 46 at the top thereof. To support the exposed portion of the band against the pressure of the roller 28, at each end of the tank adjacent the exposing slot, is a lip 47 35 which lies on the inner side of the band adjacent the side edge thereof. Water is supplied to the tank from a vacuum reservoir 48 at the back thereof, communication between the reservoir and tank being afforded 40 by a pipe 49 that opens into the tank at a point at which it is desired to maintain a constant level in the tank. As soon as the level falls enough to unseal the outlet end of the pipe, air enters the reservoir through 45 a pipe P, and a flow of water therefrom is caused. The pipe has a three-way valve 50 for opening and closing the flow from the reservoir, and draining the reservoir.

The fountain has an arm 52 that is secured to the press frame member 53, by means of a clamp that comprises a bolt 54, a block 55 and a nut 56 on the bolt between which and said block the arm 52 has a slot 57 for purposes of adjustment, and to 55 give a rigid support, the block 55 has on its side next the arm an elongated lug 58 that enters the slot.

The band driving roller 45 is rotated intermittently. At one end it has a gear 59 60 that meshes with a gear 60 loose on a shaft 61 to which a lever 62 is pivoted. The latter carries a pawl 63 that engages the teeth of the gear 60. The other arm is connected to an end of a rod 64, whose outer end has 65 an eye 65 that engages a pin or stud 66 on

the stationary member or part of the frame 10. The frame member 53 to which the arm or bracket 52 is connected, is pivoted so that it imparts a short to and fro swing to the frame, and therefore, a rocking movement is imparted to the lever 62 by reason of the connection between it and the stationary frame member formed by the rod 64 and the pin 66. The eye 65 is U-shaped and is adjustable along the rod 64 to enable the degree of travel of the band 44, to be varied and it may be easily removed from the rod. The gear 59 meshes with a gear 68 on a roller 69 below the roller 45 which roller 69 is partially submerged in the water 70 in the tank 43 and coming in contact with the belt 44 moistens the latter, this arrangement enabling a nice regulation of the amount of moisture to be transmitted to the printing plate. To protect the edges of the 75 belt 44 from the teeth of the gears 59 and 68, a thin disk 70 of larger diameter than the gear 59 is interposed between the latter and the band 44. In contact with the feeding roller 69 just before the latter comes in 80 contact with the band 44 is a roller 71 whose spindles project through slots in the end wall of the tank, and outside the latter at each end has bearings in two rods 73, which at their lower ends are threaded and 85 engaged by adjusting nuts 73 so that thereby the pressure of the roller 71 on the feed roller 69 can be regulated and thus a quantity of moisture delivered by the feed roller 69 to the band 44 regulated. 90

In starting up the press, when the plate or form is dry, it is necessary to moisten the form before applying ink thereto. This may be accomplished by preventing contact on the inking rollers with the form before 95 the dampening roller has passed over it. That may be done by providing, as best shown in Figs. 2 to 8, at each side of the chase 11, a plate 74 that is shiftable to place its outer edge into or out of the path of the 100 bearer rollers 26 on the inking rollers 24, at the time the latter traverses the form. When in their raised or elevated position, said plates keep the inking rollers from touching the form. Each plate 74 is slidably attached 105 to one side of the chase by several screws 75 that, respectively pass through upwardly and outwardly slanted slots 76 in the plate. At the lower end each plate 74 has a bearing upon a quadrant shaped cam 77 secured 110 to a rock shaft 78 pivoted in bearings at the bottom of the chase by the rocking of which shaft the cams 77 when moved in one direction lift the plates 74 and at the same time they are moved outward, or when the cams 115 are rocked in the opposite direction, the plates 74 descend and move inward into inactive position. The rock shaft has a crank arm 79 which is connected by a link 80 with a lever 81 pivoted to a bracket 82 secured to 120

125 130

some stationary part of the printing press frame and by the rocking of the lever 81, the desired lifting and lowering movements of the plates 74 are produced. It is desirable, as a matter of great convenience, to effect the movements of the plates 74 from the feed board of the printing press. I accomplish that by providing a bar 83 having a handle end 84 at the feed end of the press 5 and extending thence in a more or less irregular shape, because of the requirements of the ordinary printing press, down to a point below and reaching in rear of the lower end of the lever 81 which preferably 10 carries an anti-friction roller 85. The bar 83 has a longitudinal movement front and back of the press which is utilized to cause the rising, and falling of its rear end, or that portion which is below the lever 81; this 15 rising and falling motion being produced by a cam slot 86 in the underside of the lever, and a stationarily mounted pin or roller 87 that enters the slot. When the rear portion of the bar 83 is in its lowermost 20 position, as indicated in Fig. 8, it has no effect on the lever 81, and hence the plates 74 are in their lowered position. As indicated in Fig. 7, it acts upon the lever 81 to rock it in the direction to lift the plates 74, 25 as illustrated in Figs. 4 and 7. Pivoted to the side of the bar 83 is a plate 88 which is adapted to be rocked to the position shown in full lines in Fig. 7 where its upper edge does not project above the adjacent top portion 30 of the bar 83, or to the position shown in dotted lines which it is considerably above such top portion of the bar 83, and it is normally held in such raised position by the action of a coil spring 89 and so that a hook 35 or tooth 90 on its forward end can interlock with the stationary lug 91 projecting from the pin in which position of the parts and plates 74 being in their raised position cannot be lowered and which locking engagement takes place when the roller 85 is off 40 or out of contact with the upper edge of the plate 88. The plates 74 may be raised with the press at any position in its operation except when the impression is on, and at that 45 time the plates 74 will be automatically lowered and locked in a lowered position. When the impression is off the plates 74 may be lowered from raised position only when the rollers are in a position higher than the 50 printing plate, or from the time of going on until they leave the inking disk in going on to the printing plate, so that the spoiling of the printing plate by allowing the inking rollers to pass over it when the plate 55 is dry is prevented. To release the latch hook 90 and to lower the latch plate 88 and hold the same and the shifting bar 83 in the lower position illustrated in Fig. 8, I place on the shaft 92, with which the usual throw 60 off lever 93 is connected, a radial finger 55

which by the rocking of the shaft 92 is brought in contact with a pin 95 on the latch plate 88 and causes the swinging of the latter to disengage its hook 90 from the stop 91, and so long as by the action of the lever, 70 the finger 95 is in the position illustrated in Fig. 8, the plates 74 cannot be raised so as to form the bearers to keep the inking rollers from touching the printing plate.

In the path of each bearer-roller 41 of 75 the dampening roller as the latter traverses the form, is a bar 133, at the side of the chase, attached to the outer sides of the press frame, which is shiftable to place its forward edge to and from an advanced plane 80 so that when advanced and said rollers 41 strike and travel over it, they will keep the dampening roller out of contact with the printing form. Near the top and bottom, said bar 133 has two upwardly and rearwardly curved slots 134, which respectively are engaged by the stationary guide pins 135, to the upper of which is pivoted a lever 136 that is pivoted by a pin 137^a to said bar 133, and has a cam face 138 that projects in the path of the roller 41, so that when struck by the latter, said lever 136 will be rocked, and a bar 133 moved away 85 from position to engage said roller 41. A spring 138^a attached at one end to the lever 90 90 136, swings it in the opposite direction and thus moves the bar 133 into roller-engaging position, where it is yieldingly held. Thus when the dampening roller moves downward over the form, the bar 133 is pushed 100 out of the way and the form is moistened, but when the rollers 41 pass below their bars 133, the latter spring outward and on the ascent of the dampening roller its rollers 41 engage said bars 133 and lift the 105 dampening roller away from contact with the printing form. This operation is desirable so that no moisture will come in contact with the inked surface of the printing plate immediately before the impression is 110 taken. A latch 139, pivoted to the side of the bar 133, in position to engage the lever 136 to lock it and the bar 133 from movement, may be employed, said latch being 115 hand moved to and from such position.

With the mechanism constructed as I have thus far described it, the printing from lithographic plates can be done directly upon paper placed upon the platen, but an important object of my invention is to enable 120 offset lithography to be done upon an ordinary platen press, and I will now describe by what means I have accomplished that desirable end.

Offset lithography is done by printing 125 from the plate on a rubberized or other suitable blanket and then making the impression from the latter on the paper, and the plate of course, must be positive. In that case, therefore, the plate 15, shown in Fig. 130

2 of the drawing, would be a positive plate. Briefly described, I mount between the printing plate and the platen a revoluble frame which carries the blanket, the blanket 5 being on both sides of the frame so that one flat side of the blanket is carried against the printing plate and takes the impression therefrom, and the opposite side of the blanket having previously received an impression, prints the same upon the paper on 10 the platen.

The blanket 96 is secured to the top and bottom bars 97 of a rectangular frame, by 15 being clamped thereagainst by a strip 98 for each bar, secured thereto by screws 99. The side bars 100 of said frame are in halves, with a stud 101 on the end of one half that enters a hole 102 in the end of the other half so as to make a longitudinally slidable connection 20 to allow adjustment for the purpose of stretching the blanket on the frame with the desired tension. Each half, at its outer end has a threaded hole engaged by a screw 103 whose head engages a lug 104 on a continuous, supplemental side bar 105 lying 25 against the halves which thus provides the necessary rigidity for the sides of the blanket frame. At midlength, each side bar 105 has an outwardly projecting pintle 106, which in 30 one case is pivoted in a bar 107 and in the other case is pivoted in a similar bar 108, and said bars 107 and 108, are respectively 35 slidably mounted in grooves in the inner sides of a pair of parallel, upright stationary supports 109 and 110 that are bolted at their lower ends to the press frame 10, their upper ends extending well above the platen. Journalled at the top of the support 109 is 40 a short horizontal shaft 111, which on the inner side of the support carries a disk 112 with a diametrical slot 113, into which an oblong block 114 on the outer end of the 45 pintle 106 in the slidable bar 107 is adapted to be moved, when said bar reaches the upper limit of its sliding movement, so that disk and block are rotatably coupled and upon the turning of the disk the blanket 50 will be turned. The block 114 slides in a groove 115 in the support 109. On the other end of the shaft 111 is fixed a gear 116 with which meshes rack teeth 117 on the upper portion of a bar 118 slidably mounted on the outer side of the support 109, as by bolts or screws 119 and slots 120. At its 55 lower end the rack bar 118 has a stud or roller 121 adapted to be engaged in succession, by slots 122 in two blocks 123 clamped to the press pitman 124, and thereby the rack bar moved, first upward to revolve the 60 disk through a half turn, and then, after a proper interval, downward to turn the slotted disk 112 back a half turn. During these upward and downward motions of the pitman 124 which reciprocate the rack bar and turn 65 the blanket, the platen is motionless and as

such turning motion takes place with the blanket elevated a substantial distance above the platen, the press feeder is in no danger of harm in placing paper on and removing it from the platen. The printing takes place 70 when the blanket is in the lowered position. The rack bar 118 is latched yieldingly at each limit of movement by a spring-pressed dog 125, on the support 109 and two V-notches 126 in the rack bar which it engages in succession. 75

The blanket frame in its position for printing is latched against accidental rotation. At the extremity of each side bar 105, is a V-shaped nose 127, which in turn engages between a pair of opposing spring-held dogs 128, pivoted to a disk 129 on a cross shaft 130 journalled in the pair of bars 107 and 108 between which said shaft extends. On said shaft 130, outside the bar 85 108, is a disk 131, which is connected by a link-lever 132 to a disk 133 on the frame pintle 106 which is journalled in said frame bar 110, the connections of the link lever 132 with the two disks being excentric, and 90 diametrically opposite so that motion imparted to the disk 133 by the turning of the blanket frame will be imparted to the disk 131 in the opposite direction, and which is through a half circle. The link-lever 132 95 is fulcrumed on a pivot 134, and it is slotted to allow for longitudinal movement. Thus the latch disks 129 are revolved both to effect the locking and release of the blanket frame. The dogs 128 are spring-held to 100 allow for differential movement of the disks and frame.

The reciprocation of the blanket frame pivoting bars 107 and 108 to raise the frame well above the platen and to return it 105 to proper operating position, is produced by connections with the platen. On the underside of the platen at its inner edge near each side is an ear 134, to which is pivoted an arm 135, that extends downward 110 and at its lower end carries a pinion 136 which meshes on one side with rack teeth 137 on the frame pivoting bar, and on the opposite side with a stationary rack 138 secured in the groove in the stationary support. As the platen swings, it moves the pinion 136 with it, and the latter traveling over the stationary rack 138 is revolved and thus imparts the sliding movement to the 115 frame carrying bars 107 and 108, to an extent twice the swing of the platen.

The grippers 139 are attached adjustably to a rod 140 pivoted in the ears 134. A spring 141 with a coil about the rod, engages the gripper, at one end, and at its other end bears 125 against the arm 135 so as to cause the gripper yieldingly to press against the platen. When the platen swings upward, the rounded upper end of the arm 135 acts on a projection 142 on the gripper, and thereby lifts the gripper 130

from the platen, releasing a sheet of paper, if there, and permitting the placing of a fresh sheet for printing.

Having thus described my invention what I claim is:

1. A platen printing press having an impression receiving member, and means automatically receiving motion from a moving member of the press to present the latter first to the printing surfaces and then to paper on the platen, said platen being plane and said member having opposite plane sides.
2. A platen printing press having a revolvable impression receiving member, situated between the printing surfaces and the platen, said platen being plane and said member having opposite plane sides, and automatic means operatively connected with a moving member of the press to actuate said revolvable member.
3. A platen printing press having a revolvable impression receiving member situated between the printing surfaces and the platen, said platen being plane and said member having opposite plane sides and means automatically to revolve said impression receiving member.
4. A platen printing press having a revolvable impression receiving member situated between the printing surfaces and the platen, and means automatically to revolve said impression receiving member, through a half revolution.
5. A platen printing press having a blanket supporting frame, a pivotal support for said frame connected with and receiving movement from the platen, and means actuated by the movement of a press part for rotating said frame through a half revolution.
6. In printing apparatus of the character described, the combination of several sets of rollers, a printing surface over which they are traversable, movable plates alongside said surfaces which the rollers pass, means manually operable from the feed end of the

press for moving said plates, a throw off device, and a member under the control of the latter for rendering said means inactive.

7. In printing apparatus of the character described, the combination of traveling form moistening mechanism, and automatic means to prevent contact of the latter and the form comprising guides adjacent the form and movable to and from the path of travel of said mechanism.

8. In printing apparatus of the character described, the combination of form moistening mechanism, comprising a roller and means for reciprocating the roller over the form, and automatic means for preventing contact of the roller and the form in one direction of its travel across the form comprising guides adjacent the form and movable to and from the path of the roller-carrying mechanism.

9. In a printing apparatus of the character described, the combination of traveling roller form moistening means, a water receptacle placed below the press bed, a traveling body of absorbent material to and from which the moistening roller moves, a water reservoir and automatic means to control the supply of water to said receptacle from said reservoir comprising a pipe extending from the top of the reservoir to the receptacle.

10. A platen printing press having a revolvable impression receiving member, situated between the printing surface and the platen, in combination with a press pitman and means actuated by the latter to control the turning of said member.

11. A platen printing press having a revolvable impression receiving member situated between the printing surface and the platen, means for revolving said member, and a locking device to restrain turning of said member at a predetermined time.

In testimony that I claim the foregoing, I have hereunto set my hand.

ALBERT S. N. OLSON.
